UNITED STATES PATENT OFFICE.

FREDERICK W. HARDEN, OF PIKESVILLE, MARYLAND.

PROCESS FOR CLEANING HAIR.

1,147,720.

Specification of Letters Patent. Patented July 27, 1915.

Application filed December 30, 1914. Serial No. 879,665.

To all whom it may concern:

Be it known that I, FREDERICK W. HARDEN, a citizen of the United States, residing at Pikesville, in the county of Baltimore and State of Maryland, have invented certain new and useful Improvements in Processes for Cleaning Hair, of which the following is a specification.

This invention relates to the process of 10 cleaning hog or other short hair and removing therefrom particles of skin or animal tissue which adheres thereto.

In the processes as generally practised, the hair is subjected to the action of certain 15 solutions which dissolve or soften the cuticle and the adhering particles to such an extent that they may be readily removed. Such treatment has been found to also 20 soften the hair, whereby its strength, elasticity, or "life," is greatly impaired, thereby lessening its valuation and reducing its salability and usefulness.

With this improved process, the animal strength and elasticity of the hair is fully 25 preserved, and the particles removed therefrom produce a valuable by-product which is used as a fertilizer.

In carrying the invention into effect, the hair is subjected, while in a dry state, to a 30 thorough beating and rubbing, that is, repeatedly and successively struck and rubbed, and in a manner, that the mass of hair being treated is manipulated to cause individual hairs within the mass to pass successively between a plurality of rubbing 35 means and move toward a discharge for the finished product. At the same time, as the adhering particles or by-products are removed from the hairs, during their movement through the successive rubbing means, it is separated from the mass of hair immediately after being broken therefrom, so that, when the hairs are discharged, the by-products have been entirely removed and 40 separately discharged.

This improved process is accomplished with a machine upon which a separate application has been filed June 9, 1913, Serial No. 772,499, and said machine is constructed 50 as shown in the accompanying drawings, in which:—

Figure 1 is a side elevation. Fig. 2 is a longitudinal vertical sectional view thereof. Fig. 3 is a transverse vertical sectional view. Fig. 4 is a detail perspective view of one of the beating and rubbing teeth.

To more fully set forth this improved process, the machine illustrated in the accompanying drawings will be described in detail, and in all of the figures of the drawings, similar reference numerals designate like parts.

Referring to the drawings, 1 is the main frame of the machine supported by standards 2.

Mounted upon the main frame is a rotatable cylinder 3, supported in suitable bearings and adapted to be driven by pulley 4.

Cylinder 3 is provided with teeth 5, preferably mounted in longitudinal rows, the individual teeth of each row being spaced apart and being slightly displaced with respect to the teeth of the adjacent rows so as to form a helix extending around the cylinder. Each tooth 5 is preferably formed 75 with lateral faces 6 which converge from one vertical edge of the tooth to the other vertical edge and said faces are roughened to form rubbing surfaces. These surfaces are preferably formed to include oblique 80 ridges 7, and these ridges are arranged to slope upwardly and rearwardly from the front vertical edge of the tooth, this front edge being preferably the narrower end for reasons which will be hereinafter explained. 85

Adjacent to the lower side of cylinder 3, is mounted two concaves 8 provided with teeth 9, and it will be seen in Fig. 2, that these teeth 9 are arranged in longitudinal groups with a screen 10 therebetween. The 90 teeth of each group are preferably arranged in rows, the individual teeth of each row being displaced sufficiently longitudinally to permit the close passage therebetween of the cylinder teeth and to form rows oblique 95 to the axis of the cylinder in conformity with the helical arrangement of the cylinder teeth. These fixed teeth are preferably of the same form of the cylinder teeth.

Cylinder 3 is inclosed in a shell 11 having 100 a feed opening 12 at one end.

In order to more effectively clean the hair and avoid making the cylinders of undue length, a second cylinder 13, similar to cylinder 3, is mounted beneath the same and 105 rotated by a pulley 14, the discharge of the upper cylinder being the feed mouth of the lower one.

In operation, the hair fed into feed opening 12 is caught by the cylinder teeth and beaten downwardly and individual hairs are 110 then forced between the fixed teeth by the

cylinder teeth and the same being arranged to pass in close relation, the individual hairs are brought in contact with faces of both sets of teeth and are rubbed thoroughly therebetween and consequently the dry adhering material is cracked and broken therefrom. The mass of hair is moved bodily toward the discharge end of the machine thereby causing individual hairs to be successively beaten and rubbed, so that, when it reaches the discharge end every particle of the adhering matter has been removed. As the adhering matter is removed, it immediately sifts through the mass of hair to the screen through which it passes, thereby separating the product and by-product from each other as soon as they are disconnected. After passing through the top separator the hair passes into the bottom separator when the same operation is continued. In passing through the machine, the hairs are caught by the narrow forward edge of the cylinder teeth and given a gradual bend when brought in contact with the fixed teeth, and this combined with the roughened surfaces on the teeth crack, break, and rub from the hair all of the dry coatings clinging thereto.

It will thus be seen from the above description, that the dry covering on the hairs is cracked and broken therefrom thereby leaving the hair in a dry state with its full strength elasticity, and life.

While the process has been described as

adapted for use with short hair, it is meant to include within that term all equivalent material and substances.

Having thus described the invention, what is claimed is:—

1. The process of removing cuticle and other adherent material from short animal hair, consisting in subjecting the hair in a dry state to a thorough beating and rubbing to loosen and break the adherent material therefrom.

2. The process of removing cuticle and other adherent material from short animal hair, consisting in bending, beating, and rubbing the hair in a dry state to loosen and break the adherent material therefrom.

3. The process of removing cuticle and other adherent material from short animal hair, consisting in cracking and breaking the material from the hair while the latter is in a dry state.

4. The process of removing cuticle and other material from short animal hair, consisting in subjecting the hair in a dry state to successive beatings and rubbings to loosen and break the adherent material therefrom.

In testimony whereof I affix my signature in presence of two witnesses.

FREDERICK W. HARDEN.
